FIG. 8

WALTER L. RUTKOWSKI,
by Roy M. Eilmer ATTORNEY.

UNITED STATES PATENT OFFICE.

WALTER L. RUTKOWSKI, OF ST. LOUIS, MISSOURI, ASSIGNOR TO R. C. CAN COMPANY, OF ST. LOUIS, MISSOURI, A CORPORATION.

CAN-MAKING MACHINE.

Application filed March 10, 1922. Serial No. 542,721.

To all whom it may concern:

Be it known that I, WALTER L. RUTKOWSKI, residing at 4318 Forest Park Boulevard, in the city of St. Louis and State of Missouri, have invented certain new and useful Improvements in Can-Making Machines, of which the following is a full, clear, and exact description, such as will enable others skilled in the art to make and use the same.

10 My invention relates to improvements in can making machines and more particularly to machines for "ending", or, securing metallic bottoms and tops to can bodies.

15 My object is to provide a machine of simple construction, for ending cans, whose product is uniform and accomplished with a minimum of waste in material and with a minimum of manual effort.

20 My invention consists in the novel construction, arrangement and combination of elements as hereinafter fully, clearly and concisely described, definitely pointed out in my claims and illustrated by the accompanying drawings, in which—

25 Fig. 1 is a front elevation of a machine embodying my improvement for simple, single tool, crimping can ends to can bodies.

Fig. 2 is a side elevation of the machine shown in Fig. 1.

30 Fig. 3 is a plan view, taken on the line 3—3 of Fig. 1 and on an enlarged scale, showing in detail the means for actuating the crimping rolls or tools.

35 Fig. 4 is a transverse, sectional elevation of the means for actuating the crimping rolls, or tools as related to the means for holding the can body and can end.

40 Fig. 5, shows a fragment of a can body and a can end and the crimp on the can end as formed by a tool of which only a fragment is shown.

45 Fig. 6 is a detail, plan, view showing means for "squaring" or truing the crimping chuck, or end holding means.

50 Fig. 7 shows in side elevation a machine, of the same general design as shown in Figs. 1 and 2, in which there are distinct sets of crimping tools, or tools, for "step crimping" and means for timing the tool action.

55 Fig. 8 is a plan view showing the relation of the two sets of tools and their actuating means.

Fig. 9 is a sectional plan view as taken on the line indicated 9—9 of Fig. 7.

Fig. 10 is a rear elevation of the actuating means shown in Fig. 9.

Fig. 11 shows a fragment of a can body and can end as held and formed by the initial tools, and

Fig. 12 is a view similar to Fig. 11 showing the can end as formed by the final tools.

Referring to the drawings, 15 designates the frame of the machine as shown in Figs. 1 to 6, comprising a sleeve bearing 16 in which is slidably mounted a spindle 17 which carries at its upper end a spindle plate 18 and which plate constitutes the supporting and holding means for the can bodies to be acted upon. The plate 18 is arranged for movements to different altitudinal planes, that is from can supplying and removing position to crimping position and to this end there is provided a lever 19 having a pivotal connection 20 with the recited spindle 17 and a pivotal support 21, as best shown in Fig. 2. A second lever, 22, connected by means such as the rod 23, with an actuating pedal 24, is pivotally mounted on the recited support 21 and acts upon the lever 19 through a compensating spring 25, and the plate 18 with its actuating levers and pedal are normally held to can supplying and removing position by means such as a spring 26. A sleeve bearing 27 is carried by the machine frame above and in alignment, vertically with the sleeve bearing 16 for the spindle 17, and extended through the bearing 27 is a shaft 28 at the lower end of which is fixed the crimping chuck 29.

The shaft 28, (chuck shaft) is extended through a third bearing 30 and is capable of vertical adjustment relative to the spindle plate 18, for varying depths of can ends, by means of the clamp-collars 31 and 32, surrounding the shaft 28, at the top and bottom of the bearing 30.

Where the can bodies and their ends are of non-circular section it becomes necessary that the crimping chuck 29 precisely registers with the path defining means for the crimping tools, as will hereinafter be made clear, hence I provide a furcated extension 33 for the collar 31, carrying opposing set screws 34 and 35 arranged to bear against

an abutment 36 carried at the top of the machine frame.

Obviously upon a manipulation of the set screws 34 and 35 the chuck shaft 28 may be 5 rotatably adjusted, without vertical disturbance and consequently the chuck 29 brought and held as properly adjusted or set.

Extended through the sleeve bearing 27, 10 surrounding the chuck shaft 28 is a sleeve 37 which is rotated about the shaft 28 through bevel gears 38 and 39 by means of the pulley 40 driven as by a belt from a source of power not shown. As best shown 15 in Figs. 3 and 4 the sleeve 37 is provided with foot flanges 41 to which are pivotally mounted a pair of arms 42 which carry the crimping tools 43, each of which comprises an annulus or groove 44 whose sectional 20 contour is shaped to form the desired "crimp" of the normally flat flange 45 of the can end (as shown in Fig. 4 to the shape of the finished crimp 46 shown in Fig. 5).

In Fig. 4 I show the tools as held by means 25 such as the springs 47, to their non-functioning positions and as suspended, from their carrying arms 42, by pins 48.

For the movement of the tools, or rolls 43, to functioning, or crimping position I provide a cone 49, surrounding each pin 48 and a cam 50 comprising a bevel face for engagement with the cones 49, which cam is contoured to correspond with the margin of the can end to be acted upon by the crimping 35 rolls.

As best shown in Fig. 4 the cam 50 is arranged to move the crimping tools to crimping positions, against the tension of the springs 47, upon being moved downwardly 40 over the cones 49, and for such movement of the cam I provide a slide-block 51, supported by the machine frame 15, arranged for actuation by the recited pedal 24 through a rod 52 and a lever 53.

The direct support for the cam is, preferably, a yoke, such as 54, which is fixed to the slide block 51 and detachably connected with the cam as by means such as the screws 55.

The operation of the machine is as follows:—

Assuming the cam 50 to be in its elevated position; the crimping rolls 43 spring-held to noncrimping positions; the crimping chuck 29 properly positioned and fixed; the spindle-plate 18 in its dropped or supplying and removing position, a can body is placed upon the spindle-plate 18, and a can end loosely placed over the open, top, end of the can body and assuming further that the crimping rolls 43 are moving through paths defined by the cam 50, the operator depresses the pedal 24 and the machine automatically functions to secure or crimp the can end to the can body.

Through rod 23, lever 22, compensating

spring 25, lever 19 and spindle 17 the spindle plate 18 is elevated to bring the can end to the plane of the crimping rolls, (as shown in Fig. 4) and through rod 52, slide-block 51, and yoke 54 the cam 50 is dropped to 70 cause its bevel face to force the crimping rolls 43, through the cones 49, to engage and act upon the flange 45 of the can end.

Upon a release of the pedal, the cam 50 is elevated to permit the crimping rolls to 75 move outwardly through springs 47 and the spindle plate 18 is dropped to removing and supplying position.

I prefer that the connection between the spindle 17 and lever 19 comprises means 80 such as the clamp collar 20^a whereby the spindle 17 and consequently the can support or plate 18 may be adjusted for adaptation to can bodies of varying heights.

In the form of machine shown in Figs. 7 85 to 12, inclusive, I have provided distinct sets, or pairs, of crimping tools for progressive or step action upon the can ends and automatic means for timing the duration of the crimping action. In this form of machine the sleeve 37^a, which is identically like the described sleeve 37 in the form of machine shown in Figs. 1 to 6, is provided with a plurality of pairs of foot flanges 41^a for the pivotal support of spring actuated arms 42^a arranged to carry pins 48^a for suspending crimping rolls 43^a and 43^b.

The set of rolls 43^a as best shown in Fig. 11, act on the flange of the can end to form the initial roll or crimp and the set of rolls 43^b act on the roll or crimp to form the finished flat crimp as shown in Fig. 12.

For selective movement of the rolls 43^a and 43^b to functioning positions the pins 48^a carrying the rolls 43^a are provided with 105 cones 49^a inclining downwardly and outwardly and the pins 48^a carrying the rolls 43^b are provided with cones 49^b inclining inwardly and downwardly. These differently disposed cones are acted upon by a cam 50^a 110 having a pair of bevel faces, one of which engages the cones 49^a and the other engages the cones 49^b.

The cam 50^a is carried on a yoke like the described yoke 54 and the yoke carried on a 115 slide block like the described block 51.

In this form of machine the crimping chuck 29, is in all particulars similar to the described crimping chuck; likewise the means for bodily rotating the crimping tools 120 is similar and the spindle-plate 18 and its elevating pedal 24 are similar.

In the described machine the pedal 24 was held by the operator during the crimping interval while in this form of machine the 125 pedal depression serves merely to elevate the spindle-plate to crimping position and to initiate the movement of automatic means for holding the spindle-plate to crimping position; timing the action of the crimping 130

tools and restoring all the functioning elements to normal or starting positions.

Such automatic means I prefer to be of a type as shown, including a rock-lever 60, 5 pivotally supported by the machine frame 15, as by a bolt 61, as shown in Figs. 7 and 9, pivotally connected with the slide-block and carrying at its end, opposite the slide block a roller such as 62, for engagement in 10 slotted cam-wheel 63.

For the rotation of the cam-wheel there is provided a power driven shaft 64, having a worm gear connection with the shaft 65, 15 supporting the cam-wheel 63 which gear is controlled by a clutch 66, connected for actuation to clutching position by a rod 67 secured to the pedal 24.

On the shaft 65 supporting the cam wheel 63 is a second cam-wheel 68, in whose periphery there is formed a dwell 69, arranged for coaction with a roller 70, bell-crank 71 and rod 72 to hold the pedal 24 elevated during the crimping interval and hence the clutch 66 to "in clutch" position 25 for the rotation of the cam wheel 63 to move the cam 50°, first, to bring the initial tools 43^a to functioning positions then the tools 43^b to functioning positions, during which interval the cam wheel 68 and bell crank 71, 30 hold the pedal depressed, and consequently the clutch 66 "in clutch" and the cams 63 and 68 connected with power for their cycle of operation as determined by the movement of the dwell 69.

35 In both forms of machines illustrated, the can end is "backed" by the crimping chuck to the end that the paper can body is relieved from all torsional strains resultant from the actions of the crimping tools, 40 thereby obviating one source of annoyance

incident to other machines for this purpose.

I claim:

1. In a machine of the class described, a support for a can and can end, a crimping tool, means for bodily rotating the tool 45 around the supported can and can end, a lever for supporting the tool, a cone carried by the axis of the tool, an open ringshaped element having an inclined inner surface for engagement with said cone and means 50 for moving the ringshaped element to effect movement of the tool in a crimping direction.

2. In a machine of the class described a support for a can and can end, a lever, a crimping tool carried by said lever, a cone 55 carried by the axis of the tool, a ring shaped element shaped to define the path of the tool and having oppositely disposed faces for engagement with said cone, means for bodily 60 rotating the tool and means for bodily moving the ring shaped element to effect movement of the tool to crimping or non-crimping position.

3. In a machine of the class described, a crimping tool, means for revolving the tool in a fixed plane, a support for a can and can end, means for varying the plane of the support relative to the plane of the tool, a holding and backing element for the can end 70 fixed in the plane of the tool, an element carried by the axis of the tool, an element having a surface shaped to define the path of and surrounding the axis thereof, means for bodily moving said path defining element to effect movement of the tool to crimping position, and a spring for returning the tool to non-crimping position. 75

WALTER L. RUTKOWSKI.
